FACSIMILE-TRANSMISSION SYSTEM

Vladimir K. Zworykin, Cliffwood, N. J., assignor to Westinghouse Electric & Manufacturing Company, a corporation of Pennsylvania

Application July 5, 1928, Serial No. 376,117
Renewed August 13, 1931

6 Claims. (Cl. 178—69.5)

My invention relates to facsimile-transmission systems, and it has particular relation to systems especially adapted for the reproduction, at a distance of moving-picture films with, or without, sound accompaniment.

In my copending application, Serial No. 349,956, filed March 26, 1929, and assigned to the Westinghouse Electric and Manufacturing Company, of which this application is a continuation in part, I have disclosed an improved transmission system wherein synchronism between a scanning device at a sending station and an analogous device, comprising a cathode-ray tube, at a receiving station is automatically maintained. Certain subject-matter here disclosed is claimed in my Patent 2,141,059 and in my application Serial No. 254,607 for Facsimile transmission systems, filed February 4, 1939.

In the said system, a plurality of conductors are employed for conveying the picture-frequencies from the sending station to the receiving stations. As pointed out in the application referred to, my improved film-facsimile transmission system is adaptable to radio by the mere substitution of radio-channels for the several wire-conductors shown and by the use of a plurality of carrier waves, at different frequencies, for accomplishing the functions of synchronizing, scanning-control and propagation of the impulses representing picture-elements. Such use of a plurality of frequencies, however, is undesirable, in view of the limited number of radio-channels available, and it is, accordingly, an object of my present invention to provide a film-facsimile transmission system that shall necessitate the utilization of only a single channel for all of the functions enumerated above, irrespective of the transmitting medium, whether it be radio or wire.

Another object of my invention is to provide a film-facsimile transmission system that shall require the minimum number of carrier-channels for the transmission of moving pictures accompanied by sounds.

Another object of my invention is to provide a film-facsimile transmission system wherein synchronism between the moving parts at a sending station and homologous parts at a plurality of receiving stations shall be automatically controlled, in large measure, by the sending station while, at the same time, permitting individual control at the receiving stations if desirable.

Another object of my invention is to provide a film-facsimile transmission system wherein the timing of the control-frequencies is determined by the travel of a film, or an analogous element, past a fixed point at the sending station.

Another object of my invention is to provide a facsimile transmission system that shall be adaptable, with but minor changes, to the transmission of messages, pictures and the like, car-

ried by a continuous, opaque belt, or similar element.

Another object of my invention is to provide, in a facsimile-transmission system of the type described, means whereby a photoelectric cell shall be more efficiently utilized than in previously known systems.

Still another, and more specific, object of my invention is to provide, in a facsimile-transmission system, receiving devices that shall require the minimum of attention and adjustment on the part of the operator.

In practicing my invention, I prefer, at the sending station, to cause a motion picture film, or the like, to travel at a fixed rate of speed between an oscillating, curved mirror and a photoelectric cell. Light from a fixed source is focused by the mirror in a fine point that moves from side transversely of the moving film and, after traversing the said film, to be modulated thereby, falls upon the photoelectric cell.

A lens system is interposed between the film and the photoelectric cell cathode. The lens system is so designed that, in the absence of the moving film, an image of the mirror is focused upon the cathode of the photoelectric cell, which image does not move during the oscillation of the mirror.

At the sending station, the light-ray from the mirror is permitted to over-shoot one edge of the semi-opaque picture-area of the film and to fall upon the photoelectric cell each time it over-shoots. The output current from the photoelectric cell, therefore, has a component corresponding to the scanning-frequency of the light-ray, which frequency appears in the final output of the sending station.

At each receiving station, I provide a cathode-ray tube having a plurality of cathode-ray controlling devices disposed therein. One of the controlling devices functions to modulate the intensity of the ray in accordance with the received picture-frequencies; another of the controlling devices functions, under the control of the frequency generated by the over-shooting of the scanning-ray at the sending station, to determine the speed of horizontal movement of the cathode ray, while another of the said controlling devices is periodically de-energized, in response to an impulse sent out by the sending station each time the space between two pictures, on the film being transmitted, passes before the scanning ray. The last-named controlling-device determines the periodicity and speed of the vertical movement of the cathode ray and, automatically, adjusts the "framing" of the received picture.

The novel features that I consider characteristic of my invention are set forth with particularity in the appended claims. The invention itself, however, both as to its organization

and its method of operation, together with additional objects and advantages thereof, will best be understood from the following description of a specific embodiment, when read in connection with the accompanying drawing.

Figure 1 of the drawing is a view, partly in schematic perspective, and partly diagrammatic, of the essential elements constituting a film-facsimile sending station comprising a preferred embodiment of my invention;

Fig. 2 is a diagrammatic view of the essential elements of a receiving station comprising a preferred embodiment of my invention;

Fig. 3 is a view of a portion of a sound-and-picture film in its passage through the transmitting apparatus; and,

Fig. 4 is a diagram to which reference will hereinafter be made in describing the manner in which synchronism is secured.

The apparatus illustrated in Fig. 1 comprises a film-feeding sprocket 1 over which a motion-picture film 2 is drawn by a take-up sprocket 3. Other incidental apparatus, such as film-guiding rollers, film-magazines, film-gates, sources of motive power, belting or gearing, etc., forming no part of my invention and, further, being well known to those skilled in the art, have not been illustrated.

Light from a fixed source 4 is reflected, as a fine point, onto the film from a curved mirror 5, the focus of which lies in the plane of the film. The mirror is supported for movement about a vertical axis parallel to the film and a suitable magnetic structure 6, capable of being energized from a source 7 of alternating current, having a frequency of approximately 750 cycles per second, is provided for causing the mirror to so oscillate that the reflected ray rapidly moves from side to side, transversely of the film, as indicated by the arrow 8. It also lies within the scope of my invention to affix the mirror to a tuned reed, or to one of the tines of a tuning fork, and to excite the feed or fork from an oscillation generator of any desired type.

A photoelectric cell 10 is disposed behind the film to receive the light which is reflected therethrough from the oscillating mirror. A lens 11, or a lens-system, is interposed between the film and the photoelectric cell, the characteristics of the lens being so chosen that, in the absence of a film, an image of the entire mirror is focused on the cathode 12 of the said cell. Movement of the mirror, therefore, does not cause movement of the light spot on the cathode, from side to side and, consequently, the most sensitive portion of the cathode may be continuously utilized. This relative immovability of the light-spot is an important feature of my invention since it prevents any modulation of the output of the photo-electric cell, by the mere movement of the light ray per se from side to side, in addition to the modulation caused by the light and dark portions of the film and the "overshooting" hereinbefore mentioned.

In order to prevent the light ray from overshooting at both transparent margins of the pictures, whereby a frequency twice the scanning-frequency would appear in the output of the photoelectric cell, and to prevent a sound-record 13, if present on one of the edges of the film, from interfering with the transmission of the pictures, I interpose an opaque mask 14 between the mirror and one of the said edges, as indicated also in Fig. 3.

The output circuit of the photoelectric cell comprises a source 15 of potential, the secondary winding of a transformer 16 and a resistor 17, the said output circuit being associated with the input terminals of an amplifier 18 through a stopping condenser 20 and a conductor 21.

The amplifier is followed by a modulator 22 which, in turn, is so connected to a carrier-wave oscillation-generator 23 as to modulate the output thereof. The oscillation generator is operatively associated with a radiating system which may comprise an antenna 24, a tuning condenser 25, a coupling inductor 26 and a ground connection 27, or it may be coupled to a power line (not shown) through coupling devices of types well known to those skilled in the art.

The primary winding of the transformer 16, associated with the output circuit of the photoelectric cell, is connected from ground, through a source of alternating potential 28, to a fixed contact-device 30. The fixed contact-device is normally disassociated from a movable contact 31 carried by a pivotally supported arm 32. One end of the arm is slightly curved upwardly and is disposed in the path of travel of a plurality of cam-surfaces 33 carried by a disk 34 which is mounted upon a rotatably supported shaft 35 having a ground connection 36.

In addition to the said disc, the shaft carries a sprocket-wheel 37 having teeth which are spaced to correspond with marginal openings 38 in the film, the said sprocket-wheel being so disposed with respect to the path of travel of the film that it is caused to rotate thereby.

The number of teeth in the sprocket wheel is so correlated to the number of cam surfaces 33 that, at each instant when the space between any two picture-frames passes through the path of travel of the scanning ray, the pivoted arm 32 is raised to complete a circuit permitting potentials at the frequency of the alternating potential source 28 to be impressed across the primary winding of the transformer and, consequently, to induce corresponding potentials across the input circuit of the amplifier 18. In order that "framing" of the picture may be expeditiously accomplished at the transmitter, in the event that the sprocket holes are not properly spaced with respect to the picture-elements, it is desirable to provide the arm 32 with supporting means (not shown) whereby it may be so adjusted, circumferentially of the disc 34, that the framing impulses occur earlier, or later, in the travel of the film.

In the operation of the sending station just described the film, in its travel from the storage-reel to the take-up reel, is subjected to the oscillating scanning ray from the mirror, which ray, after its passage through the film, falls upon the photoelectric cell to modulate the output therefrom in accordance with the transparent and opaque portions of each picture-frame. During those instants when the opaque space between two frames passes through the path of the scanning-ray, the circuit including the source 28 is closed, by the movement of the pivoted arm 32, and the output of the transmitter is, accordingly, modulated at the frequency of the said source. The manner in which the periodic modulation of the carrier-wave is utilized, at the receiving stations, will be explained, in detail, later.

Each time the scanning-ray overshoots, the margin of the film that is not shielded by the mask, a momentarily larger pulse of current ap-

pears in the output circuit of the photo-cell, these current-pulses being at the scanning frequency.

The carrier-wave is, therefore, also modulated at the scanning-frequency, which modulation is utilized, at the receiving stations, to control a similar scanning operation. It should be clearly understood from the foregoing description, that the frequencies representative of the picture, the scanning-frequency impulses and the impulses introduced into the amplifier from the source 28 do not overlap, but are separated, each from the others, by definite time-intervals. The carrier wave, therefore, is modulated by these three frequencies which, hereinafter, will be designated always as picture, scanning and framing frequencies, respectively, without the slightest interference existing between them.

The apparatus at a receiving station comprises an energy receptor constituted by an antenna 50, a tuning condenser 51, an inductor 52 and a ground connection 53. The energy receiving circuit is coupled to a radio-frequency amplifier 54, of any suitable type, which amplifier is followed by a detector and audio-frequency amplifier 55. The output from the audio-frequency amplifier is impressed upon a filter 56 which passes the framing-frequency only, a second filter 57 which passes the scanning-frequency and upon the primary winding of a transformer 58.

The receiving apparatus further comprises a cathode-ray tube 60 of the type having a thermionic cathode 61, a control-electrode 62, an anode 63, a plurality of plates 64 and 65 for deflecting the electron stream in a direction indicated by the arrows A—B, and a plurality of plates 66 and 67 for deflecting the electron stream in a direction C—D at right angles to the direction A—B. The control electrode 62 of the tube is connected to the cathode thereof through a source 68 of biasing potential and the secondary winding of the transformer 58.

Although I have shown the controlling plates 64, 65, 66 and 67 as being disposed within the tube, it should be distinctly understood that the said plates may be supported exteriorly thereof and that deflecting coils may be substituted for the plates 64 and 65 without departing from the spirit of my invention.

The potential gradient between the control electrode of the cathode-ray tube and the cathode thereof comprises two components, an unidirectional biasing-potential from the source 68 and an alternating potential, representative of the picture-modulation of the incoming signal from the transformer 58. Since the magnitude of the electron stream between the cathode and the anode is a function of the potential between the control electrode and the cathode, and since the brilliance of the fluorescence of the screen at the end of the tube is at very instant a function of the magnitude of the electron stream, or cathode ray, passing through the anode, the said brilliance is always proportional to the picture modulation.

The deflecting plate 65 is connected to ground, and the opposite deflecting plate 64 is connected, by a conductor 78, to the anode 71, of a thermionic device 72, so disposed and connected as to normally generate oscillations at the scanning frequency.

The input circuit of the thermionic device comprises a resistor 73 which is included in the output circuit of the scanning-frequency filter 57. The scanning-frequency modulation of the car-

rier wave, impressed thereon by the overshooting of the scanning-ray, when impressed upon the input circuit of the oscillation generator 72, tends to pull it into synchronism therewith. The deflection of the cathode ray in the receiver in the direction of the arrow A—B is, accordingly, automatically maintained in step with the movement of the scanning ray at the transmitting station.

The plate 67, of the pair of plates in the cathode-ray tube that control the deflection of the electron stream in the direction of the arrows C—D, is connected to ground, and the opposite plate 66 is connected, by a metallic conductor 74 to the anode 75 of a thermionic rectifying device 76, the cathode 77 of which is connected to ground through a source of potential 78. A plurality of adjusting condensers 80 and 81 are connected, in shunt, to the condenser constituted by the deflecting plates 66 and 67 and, therefore, in shunt to the cathode and anode of the rectifying device 76.

The function of the rectifying device is to build up a charge upon the deflecting plates 66 and 67, and upon the condensers 80 and 81 in order that the cathode ray shall be deflected, in the direction of the arrows C—D, proportionally thereto. The deflection of the said ray in the direction C—D corresponds to that coordinate of the scanning operation at the transmitting station which is introduced by the motion of the film longitudinally thereof. The size of the adjusting condensers 80 and 81 and the potential of the source 78 are so chosen that the charge upon the deflecting plates in the Braun tube will build from zero to the desired maximum during the time required for the film at the transmitter to travel a distance corresponding to the advance of a single picture frame past the path of the scanning-ray.

The charging current is limited by the emission of the cathode of tube 76 and, therefore, the condensers 80 and 81 are charged at straight linear charge as shown in Fig. 4.

Accordingly, if at the instant the light from the oscillating mirror starts to traverse in a given picture frame, the charge upon the deflecting plates 66 and 67 is zero, or substantially zero, the successive portions of the path traced by the scanning ray on a single picture-frame of the film will be represented by successive shifts of the electron stream in the Braun tube in the direction of the arrows C—D.

In order, therefore, that the deflecting plates 66 and 67 shall be completely discharged at the beginning of the scanning operation of each individual picture-frame at the transmitter, means are provided whereby their charge is controlled by the framing-frequency impulses sent out by the transmitting station each time the framing-frequency generator is permitted to modulate the carrier-wave through the action of the cam-disc 34 and the pivoted contact device associated therewith.

The charge-control means for the deflecting plates, preferably, comprises a short-circuiting device connected in shunt thereto and responsive to the framing-frequency impulses. For this purpose I have advantageously employed a grid-glow tube 90, having a plurality of cold electrodes namely, an anode 91, a cathode 92 and a grid 93, and being of the type disclosed and claimed in the copending application of Dewey D. Knowles, Serial No. 149,290, filed November 19, 1936, and assigned to the Westinghouse Electric and Manufacturing Company. The grid-glow tube has the property of changing from a non-conductive to a

conductive state, depending upon the potential applied to the grid thereof, with substantially inappreciable time-lag.

The input circuit of the grid-glow tube comprises a resistor 84 and a source 85 of potential for biasing the device, normally, to the non-conductive state. The resistor is included in series with a condenser 86, in the output circuit of the framing-frequency filter 56.

Each incoming impulse at the framing-frequency impressed across the condenser, overcomes the bias from the source 85, causes the grid-glow tube to assume the conductive state and to, accordingly, deprive the deflecting plates 68 and 69 of the charge they have acquired during the scanning of a single picture-frame at the transmitter.

The periodic charge and discharge of the deflecting plates is illustrated graphically in Fig. 4, wherein distances on the Y axis represent potentials existing across the said plates, and distances across the X axis are representative of the time.

From an inspection of Fig. 4, it will be noted that the potential across the plates is indicated as rising gradually from zero to its maximum in a period of one-twentieth of a second, and then dropping quickly to zero to again repeat. The charging period indicated corresponds to a film speed of substantially 20 pictures per second, which speed is satisfactory for the transmission of film-facsimiles with the illusion of motion. If it is desired to transmit a combined picture and sound film, the film speed may be increased and the condensers 88 and 89 may be reduced in capacity proportionally in order that they shall so acquire their charge in a shorter space of time.

The scanning frequency has been indicated as 750 cycles per second, and the framing-frequency as 1200 cycles per second. These frequencies are not at all fixed, however, it being only necessary that the frequency of scanning be sufficiently different from the framing frequency that they may be separated easily at the receiver.

Although the framing of the received picture in the direction C—D is automatically accomplished through the medium of the controlled oscillation generator 72, it is feasible to superimpose a certain measure of manual control at the receiving end. One way in which this may be accomplished is by momentarily altering the capacity of the condenser 81, which influences the rate at which the deflecting plates 68 and 69 receive their charge from the rectifying device. A certain measure of control may also be had by varying the resistor 84 connected across the input terminals of the grid glow tube, by manipulating a variable condenser 100 connected in shunt to the transformer which impresses the framing-frequency across the rectifier, or by altering the potential supplied by the source 78 connected to the rectifying device.

My improved film-facsimile transmission system is not restricted to use in connection with translucent films, since by merely substituting an optical system of the reflection type, such as is illustrated in my copending application Serial No. 317,599, filed November 6, 1928, and assigned to the Westinghouse Electrical and Manufacturing Company, the system is rendered adaptable to the transmission of a series of pictures, messages and the like mounted upon and carried by an opaque element, such as a belt.

My invention is also adaptable to television

systems wherein a visual image of a moving object, such as a person, is produced at a distant point. In such case, the object may be scanned, in one direction, by a ray of light from a rapidly oscillating mirror, the said ray, in its passage from the mirror to the object, being reflected from the surface of a slowly rotating, polygonal mirror to cause it to move slowly in a direction at right angles to the first-mentioned direction. Means, equivalent to the cam-disc 34 and the arm 32, may be associated with the polygonal mirror to send the framing impulses whenever the ray reaches the end of its slow travel, thus introducing the component of the scanning operation provided for by the movement of the film in the system hereinbefore described. The scanning frequency may be developed, in the output of a photoelectric cell in the modified system, by disposing either a bright surface or a dull surface at one side of the object, on which the scanning ray falls when it overshoots.

My improved facsimile transmission system is mainly advantageous in that it permits the utilization of a single carrier wave for the propagation of the picture frequencies and all of the necessary synchronizing frequencies as well.

Another important advantage of my improved system lies in the disposition of the lens system between the film and the photoelectric cell, whereby the image of the mirror does not move, at the point where it falls upon the cell, even though the point of light focused by the mirror is moving transversely of the film. The movement of the ray per se, accordingly, across the space normally occupied by the film, does not cause any modulation of the photo-cell output and the generation of interfering harmonic frequencies is thus prevented.

Although I have chosen a specific embodiment of my invention for purposes of illustration and description, modifications thereof will be apparent to those skilled in the art. My invention, therefore, is not to be restricted except insofar as is necessitated by the prior art or by the spirit of the appended claims.

I claim as my invention:

1. In a facsimile transmission system, means for continuously subjecting an object to a scanning-ray, means energized by said ray for generating a synchronizing frequency and means controlled by said object for generating an additional synchronizing frequency.

2. In a facsimile-transmission system, means for moving an object, means for subjecting said object to the action of a scanning-ray, means for generating a carrier-current and for modulating it in accordance with the scanning ray as modified by said object, and means whereby said object and said ray cooperate to generate a synchronizing frequency for modulating said carrier-current, and additional means controlled by the movement of said object for periodically modulating said carrier-current.

3. The apparatus covered in claim 1 in combination with receiving means comprising a scanning device responsive to both of the said synchronizing frequencies.

4. The apparatus covered in claim 2 in combination with receiving means comprising a scanning device responsive to the synchronizing frequency and to the said periodical modulation of the carrier current.

5. In combination, a tube of the cathode ray type having means in proximity thereto for deflecting said cathode ray, a storage condenser

connected to said deflecting means, a source of potential, an impedance connecting said source of potential and said condenser, a source of signalling current, and a grid glow tube having an output circuit connected to said condenser and an input circuit connected to said source of signalling current.

6. In a television receiver, scanning means

comprising a grid controlled gaseous discharge tube, a charging and storage circuit associated therewith, and means responsive to signaling impulses above a predetermined amplitude only for initiating a gas discharge and permitting said storage circuit to relieve itself.

VLADIMIR K. ZWORYKIN.
